(57) **CLAIM**

The ornamental design for an electrical connector, as shown and described.

DESCRIPTION

FIG. 1 is a top, right side perspective view of an electrical connector, showing my new design;

FIG. 2 is a bottom, left side perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a right side view thereof;

FIG. 8 is a left side view thereof;

FIG. 9 is an enlarged view of area 9 in FIG. 3 thereof; and, FIG. 10 is an enlarged view of FIG. 4 thereof.

The dash-dash broken lines in the drawings illustrate both portions of the article and environmental subject matter that form no part of the claimed design. The dash-dot-dot broken lines illustrate the bounds of the portion shown enlarged in the drawings, and form no part of the claimed design. The shading in the figures shows contour and not surface ornamentation.
